(57) CLAIM

The ornamental design for a receiver housing, as shown and described.

DESCRIPTION

FIG. 1 is a perspective view of a receiver housing with the front cover open, showing my new design;

FIG. 2 is a top view of the present invention with its front cover open;

FIG. 3 is a front view of the present invention with its front cover open;

FIG. 4 is a bottom view of the present invention with its front cover open;

FIG. 5 is view of a right side of the present invention with its front cover open, the left side being a mirror image;

FIG. 6 is a front perspective view of the present invention with its front cover closed;

FIG. 7 is a front view of the present invention with its front cover closed; and,

FIG. 8 is a view of the right side of the present invention with its front cover closed, the left side being a mirror image. The broken lines in FIG. 1 are for illustrative purposes only and form no part of the claimed invention.
